UNITED STATES PATENT OFFICE

132,920

DESIGN FOR A MECHANICAL PENCIL

Trace Christenson, Jr., Evanston, Ill., assignor to
Autopoint Company, Chicago, Ill., a corpora-
tion of Illinois

Application July 11, 1941, Serial No. 102,029

Term of patent 7 years

To all whom it may concern:

Be it known that I, Trace Christenson, Jr., a citizen of the United States, residing at Evanston, in the county of Cook and State of Illinois, have invented a new, original, and ornamental Design for a Mechanical Pencil, of which the following is a specification, reference being had to the accompanying drawing, forming a part thereof.

In the drawing:

Fig. 1 is an enlarged side elevation of a mechanical pencil embodying my design.

Fig. 2 is a view similar to Fig. 1 except omitting the cap and showing the pencil rotated through 90° from the position shown in Fig. 1.

Fig. 3 is a side elevation of the cap.

Fig. 4 is a top plan view of the pencil shown in Fig. 1.

I claim:

The ornamental design for a mechanical pencil, as shown and described.
